DESIGN FOR A COASTER WAGON

John G. Rideout, Perrysburg, Ohio, assignor to
The American-National Company, Toledo,
Ohio, a corporation of Ohio

Application April 13, 1935, Serial No. 56,363

Term of patent 7 years

To all whom it may concern:

Be it known that I, John G. Rideout, a citizen of the United States and resident of Perrysburg, in the county of Wood, State of Ohio, have invented a new, original, and ornamental Design for a Coaster Wagon, of which the following is a specification, reference being had to the accompanying drawing, forming a part thereof.

Fig. 1 is a side elevation of a coaster wagon, showing my new design;

Fig. 2 is a top plan view thereof, a portion of the tongue being broken away for convenience of illustration; and

Fig. 3 is a front elevation, with the tongue partly broken away.

The essential feature of the design resides in the box portion shown in full lines.

I claim:

The ornamental design for a coaster wagon, substantially as shown and described.

JOHN G. RIDEOUT.
